(57) **CLAIM**

The ornamental design for a lighting fixture, as shown and described.

DESCRIPTION

FIG. 1 is a top front right perspective view of a lighting fixture showing a first embodiment of our new design;

FIG. 2 is a front view thereof, the rear view being an identical view thereof;

FIG. 3 is a right side view thereof, the left side view being an identical view thereof;

FIG. 4 is a top view thereof;

FIG. 5 is a bottom view thereof;

FIG. 6 is a bottom front right perspective view thereof;

FIG. 7 is a top front right perspective view of a lighting fixture showing a second embodiment of our new design;

FIG. 8 is a front view thereof, the rear view being an identical view thereof;

FIG. 9 is a right side view thereof, the left side view being an identical view thereof;

FIG. 10 is a top view thereof;

FIG. 11 is a bottom view thereof; and,

FIG. 12 is a bottom front right perspective view thereof.

The dot-dot broken lines representing the remainder of the lighting fixture are for illustrative purposes only and form no part of the claimed design.
